(US) LLP(57) **CLAIM**

The ornamental design for a fluid end for a pumping system substantially as shown and described.

DESCRIPTION

FIG. 1 is a front perspective view of a fluid end;
FIG. 2 is a back perspective view of the fluid end;
FIG. 3 is a front view of the fluid end;
FIG. 4 is a back view of the fluid end;
FIG. 5 is a left side view of the fluid end;
FIG. 6 is a right side view of the fluid end;
FIG. 7 is a top view of the fluid end; and,
FIG. 8 is a bottom view of the fluid end.
The broken lines in the drawings depict portions of the fluid end for a pumping system and form no part of the claimed design.
